UNITED STATES PATENT OFFICE.

MONROE S. MAYFIELD, OF EAST ST. LOUIS, ILLINOIS.

DESIGN FOR A ROCK-CANDY CONFECTION.

Application filed June 23, 1927. Serial No. 22,535. Term of patent 3½ years.

To all whom it may concern:

Be it known that I, MONROE S. MAYFIELD, a citizen of the United States, and a resident of East St. Louis, St. Clair County, Illinois, have invented a new, original, and ornamental Design for a Rock-Candy Confection, of which the following is a specification, reference being had to the accompanying drawing forming part hereof, in which—

Fig. 1 is a top plan view of the confection; and Fig. 2 is a side elevation thereof.

I claim:

The ornamental design for a rock-candy confection substantially as shown.

In testimony whereof I have signed my name to this specification this 21st day of June, 1927.

MONROE S. MAYFIELD.
